UNITED STATES PATENT OFFICE.

REINHOLD KRUMMING, OF MILWAUKEE, WISCONSIN.

SCORING OR CRIMPING MACHINE FOR SHEETS OR LEAVES.

1,178,735.

Specification of Letters Patent. Patented Apr. 11, 1916.

Application filed January 5, 1914. Serial No. 810,360.

To all whom it may concern:

Be it known that I, REINHOLD KRUMMING, a citizen of the United States, residing at Milwaukee, Wisconsin, have invented certain new and useful Improvements in Scoring or Crimping Machines for Sheets or Leaves, of which the following is a specification.

This invention relates to improvements in scoring or crimping machines for sheets or leaves.

Sheets or leaves used for record books are commonly of quite heavy stiff paper. When such sheets are used in temporary binders or loose leaf holders of certain well-known types, the sheets do not, owing to the manner in which they are bound or retained in the binders, lie flat unless some special provision is made for hinging or flexing portions in the sheets adjacent their binding margin. Further, this objection of not lying flat is sometimes found in permanently bound books having sheets of this heavy stiff character.

The main objects of my invention are: First, to provide an improved means for crimping or scoring sheets or leaves to produce hinge or flexing portions therein adjacent their binding margins. Second, to provide an improved printing machine attachment which scores or crimps sheets or leaves to produce suitable flexing or hinging portions therein during the printing of the sheets. Third, to provide an improved means or attachment having these advantages, which is simple and economical in structure, and very easy to operate.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is a front view of a structure embodying the features of my invention, one cylinder only of a cylinder printing machine and a portion of the frame being shown. Fig. II is a detail vertical section on a line corresponding to the line 2—2 of

Fig. I. Fig. III is a detail plan view of a sheet produced by my improved machine. Fig. IV is a detail section of a sheet on a line corresponding to line 4—4 of Fig. III. Fig. V is a plan view of a modified form of my invention, showing the same adapted to a bed press. Fig. VI is an enlarged detail section on a line corresponding to line 6—6 of Fig. V.

In the drawing, similar reference characters refer to similar parts throughout the several views, and the sectional views are taken looking in the direction of the little arrows at the ends of the section lines.

Referring to the drawing, 1 represents the frame of a cylinder printing machine and 2 one of its cylinders. These parts are shown in conventional form only.

The crimping or scoring rollers 3 are provided with a plurality of annular A-shaped blades. These rollers 3 are carried by arms 4 having journals 5 projecting to one side from their inner ends. The arms 4 are mounted for longitudinal adjustment on the rod 6. This rod 6 is supported by the brackets 7 at the side of the cylinder 2, the brackets being mounted on the frame by means of bolts 8. The arms 4 are secured in their adjusted positions on the rod by means of the collars 9 provided with set screws 10, there being a collar at each side of each arm. See Fig. I. The arms project outwardly at 11 beyond the rods and are provided with laterally projecting portions 12 with which the adjusting screws 13 engage. These adjusting screws are arranged through the bar 14 arranged on the brackets 7 parallel with the rod 6. The screws 13 are provided with lock nuts 15 and with holes 16 adapted to receive an adjusting tool. These set screws hold the rollers against the printing cylinder with sufficient pressure to accomplish the purpose.

Arranged on the cylinder opposite the rolls is a series of resilient pads 17. The pads 17 are arranged on the cylinder in a spaced relation so that there is an unscored portion 20 between each group of scores, as shown in Fig. III, in which the sheet 18 has two groups of scores 19, there being an unscored portion 20 between the groups and between the edge of the sheets and the scores. The sheet is scored on both sides, as shown in Fig. IV, the scoring on opposite sides being alternated. This is accomplished by setting

the rollers in the desired position to produce the scores on one side when the sheet is printed on that side and then setting crimping rollers over so that when the sheet is printed on the other side it is scored on that side, the scorings coming between those formed previously, as stated.

By printing, I contemplate the headings and not in ordinary practice the ruling of 10 the sheet, as the sheets are preferably ruled before printing the headings and forming the flexible hinge or flexing portions. By this means I produce a sheet which has a very flexible hinge or flexing portion and at 15 the same time, one which is not likely to break in use or be torn in handling, and the sheets are very economical to produce.

In Figs. V and VI, I show my improvements adapted to a bed or platen machine in 20 which the crimping or scoring knives 21 are locked up in a form, as 22, with the type 23 which is indicated in a conventional manner. The blades or knives 21 are arranged side by side, preferably with removable leads 25 or slugs 24 at the sides thereof, so that the slugs may be removed or shifted to set over the knives when it is desired to print and score the sheets on the opposite sides. The quoins 25 are shown in conventional form.

30 From the foregoing, it will be obvious that my improvements are capable of embodiment in various relations to meet the particular requirement. I have illustrated and described my improvements in detail in 35 a simple embodiment and have not attempted to illustrate all the modifications I contemplate as I believe the disclosure made will enable those skilled in the art to embody my improvements as circumstances may dictate.

40 Having thus described my invention, what I claim as new and desire to secure by Letters Patent is:

1. The combination with a printing machine comprising a frame and a printing cylinder, of brackets mounted on said frame, 45 a rod supported by said brackets at the side of said cylinder, crimping or scoring roller supporting arms mounted for longitudinal adjustment on said rod, with their ends 50 projecting outwardly beyond the rod, collars on said rod at each side of said arms, said collars being provided with set screws whereby they are retained in their adjusted 55 positions, crimping or scoring rollers having a plurality of A-shaped annular blades thereon journaled on said arms, a bar mounted on said brackets parallel with said rod, adjusting screws carried by said bar engaging the outwardly projecting ends of 60 said arms, and resilient pads circumferentially arranged on said cylinder opposite said rollers, there being spaces between the pads.

65 2. The combination with a printing machine comprising a frame and a printing

cylinder, of brackets mounted on said frame, a rod supported by said brackets at the side of said cylinder, crimping or scoring roller supporting arms mounted for longitudinal adjustment on said rod, with their ends projecting outwardly beyond the 70 rod, collars on said rod at each side of said arms, said collars being provided with set screws whereby they are retained in their adjusted positions, crimping or scoring 75 rollers having a plurality of A-shaped annular blades thereon journaled on said arms, a bar mounted on said brackets parallel with said rod, and adjusting screws carried by said bar engaging the outwardly 80 projecting ends of said arms.

3. The combination with a printing machine comprising a frame and a printing cylinder, of brackets mounted on said frame, a rod supported by said brackets at the side 85 of said cylinder, crimping or scoring roller supporting arms mounted for longitudinal adjustment on said rod, crimping or scoring rollers having a plurality of A-shaped annular blades thereon journaled on said arms, a bar mounted on said brackets parallel with 90 said rod, adjusting screws carried by said bar engaging said arms, and resilient pads circumferentially arranged on said cylinder opposite said rollers, there being spaces 95 between the pads.

4. The combination with a printing machine comprising a frame and a printing cylinder, of brackets mounted on said frame, a rod supported by said brackets at the side 100 of said cylinder, crimping or scoring roller supporting arms mounted for longitudinal adjustment on said rod, crimping or scoring rollers having a plurality of A-shaped annular blades thereon journaled on said arms, a bar mounted on said brackets parallel with 105 said rod, and adjusting screws carried by said bar engaging said arms.

5. The combination of a cylinder, a rod supported at the side of said cylinder, a 110 crimping or scoring roller supporting arm mounted for longitudinal adjustment on said rod, a crimping roller having a series of blades journaled on said arm, an adjusting screw for said arm, and resilient pads 115 arranged on said cylinder opposite said roller, there being spaces between the pads.

6. The combination of a printing cylinder, a rod supported at the side of said cylinder, a crimping or scoring roller supporting arm mounted for longitudinal adjustment on 120 said rod, a crimping roller having a series of blades journaled on said arm to coat with said printing cylinder, and an adjusting screw for said arm.

7. The combination of a cylinder, a crimping or scoring roller having a series of 125 blades supported for adjustment longitudinally of the cylinder, a screw for adjustably supporting said roller against said cylinder,

and resilient pads circumferentially arranged on said cylinder opposite said roller, there being spaces between the pads.

8. The combination of a printing cylinder, 5 a crimping or scoring roller having a series of blades supported for adjustment longitudinally of the cylinder, a screw for adjustably supporting said roller against said printing cylinder, and a pad arranged on 10 said cylinder opposite said roller.

9. The combination of a printing member,

and a series of crimping blades coating therewith, said blades being supported for lateral adjustment.

In witness whereof, I have hereunto set 15 my hand and seal in the presence of two witnesses.

REINHOLD KRUMMING. [L.S.]
